United States Patent Office

Des. 194,922
Patented Apr. 2, 1963

194,922

DUPLICATE BRIDGE BOARD OR SIMILAR ARTICLE

Clyde R. Stein, Los Angeles, Calif., assignor to
Frederick H. Flam, Tarzana, Calif.

Filed Sept. 24, 1962, Ser. No. 71,826

Term of patent 14 years

(Cl. D34—13)

FIG. 1.

FIG. 2.

FIG. 3.

FIG. 4.

FIG. 5.

FIG. 1 is a perspective view of a duplicate bridge board or similar article incorporating my new design;

FIG. 2 is a top plan view thereof;

FIG. 3 is a side elevational view of the lower side of FIG. 2;

FIG. 4 is a side elevational view of the upper side of FIG. 2; and

FIG. 5 is an end elevational view thereof.

I claim:

The ornamental design for duplicate bridge board or similar article, substantially as shown.
